UNITED STATES PATENT OFFICE.

JOHANNES BENJAMIN EEN, OF VOSS, NORWAY.

BUILDING STRUCTURE.

1,371,744.

Specification of Letters Patent.

Patented Mar. 15, 1921.

Application filed February 18, 1920. Serial No. 359,536.

To all whom it may concern:

Be it known that I, JOHANNES BENJAMIN EEN, a subject of the King of Norway, residing at Voss, Norway, have invented 5 certain new and useful Improvements in Building Structures; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 This invention relates to building structures, and more particularly to structures built up of sections which are manufactured in standard types and transported to the site on which they are to be erected, the principal object of the invention being to provide 20 a structure of this character having means for readily and effectively interconnecting the sections and at the same time providing air-tight joints between said sections.

25 In the drawings accompanying and forming part of this specification,

Figure 1 is a vertical sectional view illustrating the interconnection of two superposed wall sections and their connection with the joists for supporting an intervening floor;

Fig. 2 is a horizontal section taken at the corner of a structure built in accordance with the present invention, and illustrating 35 the interconnection between two side walls at right angles to each other.

The same characters of reference designate the same parts in the different figures of the drawings.

40 Referring to the drawings, and particularly to Fig. 1, the reference numeral 3 designates the top plate of the framework of a lower room, the outside and inside sheathing forming the walls of which are designated by the reference numerals 2 and 1 respectively. 45 14 designates what may be termed the sill of the frame of an upper room, also having a double wall formed of outside and inside sheathing 10 and 9 respectively. The member 3 has formed in its upper side a longitudinally extending rabbet 4, the side wall of the projecting portion 5 of which is inclined. 6 designates one of the floor joists, a number of which are 50 spaced apart along the length of the plate 3. Each of the joists 6 is provided with a re-

cess or groove in its lower edge, as indicated at 7, said groove being provided with inclined side walls, thus providing near the end of the joist a portion 6^a adapted to project into the rabbet of the plate 3 and interlock with the side wall of the projecting portion 5. It will be observed that the recess or groove in the joist 6 is of sufficient length to straddle the projecting portion 5 of the 65 plate 3 as well as the inside sheathing 1 and still leave an open groove between said sheathing and the side wall of the groove in the joist 6 for the reception of the wedge-shaped portion of a list member 8, by means 70 of which the joists are all locked into the rabbet of the top plate 3, the list 8 being secured in position by means of nails or any other suitable fastening means.

It will be obvious that the joist 6 could 75 be interlocked with the member 14, which I have termed the sill of the upper floor, in identically the same manner as it is locked in connection with the plate 3. In the present instance, however, I have illustrated the 80 sill 14 provided with a longitudinally extending recess or groove 13, the side walls of which are preferably inclined, and the joists 6 are each provided with a transverse rabbet at the end thereof and a recess spaced 85 from said rabbet a sufficient distance to provide a projecting portion 12 which fits into and interlocks with the wall of the recess 13. The recess formed in the upper edge of the joist 6 is, like the groove 7 in the lower edge thereof, of sufficient width to straddle the projecting portion 14^a of the sill 14 at one side of the groove 13, together with the inside sheathing 9 and leave a space at the inner side of said sheathing for the reception 90 of the wedge-shaped edge of a list member 15 which locks the sill 14 and the joists 6 together. The structure is provided at the exterior thereof with a moisture shedding member 11 extending longitudinally of the 100 members 3 and 14 and bridging the joint between said members, said moisture shedding member being preferably formed with a rabbet at its lower edge to overlap the lower outside sheathing 2 and at its upper edge 105 inclined to fit under the inclined ends of the upper outside sheathing 10.

Referring now to Fig. 2, which illustrates the manner of interlocking the side walls at the vertical corners of the structure, the 110 corner studs 21 and 22 are formed with interlocking longitudinal rabbets forming

interengaging portions as shown at 23. In this figure, A designates the horizontal beams forming the sill at the ground floor of the structure, and 18 designates a portion 5 of the outside sheathing. The stud 22 is of a width greater than that of the stud 21 so as to provide a space between the outer side of the stud 21 and the inner side of the vertical corner board 17 equal to the thickness 10 of this outer sheathing 18, whereby the end of said sheathing snugly fits between the stud 21 and the corner board 17, as shown at the left-hand side of Fig. 2. A second vertical corner board 17 is secured to the 15 outer side of the stud 22, with the sheathing 18 between it and said stud at right-angles to the first board 17. The inside sheathing 1 forming one side wall is secured to the stud 21 and the sill A with one of its vertical edges abutting the stud 22, while the sheathing forming the wall at right angles thereto has its vertical edge tapered and spaced some distance from the corner formed by the other sheathing 1 and the 20 stud 22. A corner fillet or list 25 is provided with a projecting wedge-shaped portion 26 which enters the space so formed and retains the studs 21 and 22 in interlocked engagement.

25 It will be observed that in the present instance, at every corner where a list member is used for retaining the parts of the structure in interlocking engagement, the wedge portion of the list does not entirely fill the space provided for it. The unoccupied space 30 may, if desired, be filled with a packing material 27, such as oakum or the like, as shown in Fig. 2. It will also be observed that in each of the joints illustrated in the 35 drawings, the frame members are provided with interengaging portions having inclined side walls, and that means is provided for coöperating with one of said portions to form a groove of greater width than the 40

other of said portions thereby to provide 45 space for a wedging member. In the form herein shown, this coöperating means comprises the inner walls of groove 7 and of the groove receiving portion 14^a in Fig. 1, and the tapered end of the sheathing in 50 Fig. 2.

It will be understood, of course, that the interlocking walls of the interengaging portions of the frame members may be of any suitable formation other than inclined, such 55 for instance as stepped, the object to be attained being to prevent disconnection of the frame members after they have been wedged into interlocking relation, the essential feature of the invention being the formation 60 of interengaging portions in the frame members and locking them in place by means of wedge-shaped members, thereby providing a secure but readily detachable interconnection 65 between the sections of the building structure.

Having thus described my invention, what I claim is:

In a joint for connecting the meeting ends 70 of parts of a building, a frame member having a laterally projecting portion, means associated with said member and spaced from said portion to form a groove, a second frame member provided with a projecting portion received in said groove and engaging the 75 first mentioned portion, an inner sheathing received endwise in said groove, and a list member engaging said means and said sheathing and locking said sheathing and the second mentioned portion in said groove. 80

In testimony that I claim the foregoing as my invention, I have signed my name in presence of two subscribing witnesses.

JOHANNES BENJAMIN EEN.
